J. F. BRAY

STEAM BOBBINS

Filed April 5, 1927

UNITED STATES PATENT OFFICE.

JOSEPH F. BRAY, OF WESTERLY, RHODE ISLAND.

STEAM BOBBIN.

Application filed April 5, 1927. Serial No. 181,145.

This invention relates to bobbins such as are used in winding machines and where it is desired to moisten the yarn or thread by the application of steam thereto. Bobbins which 5 are usually made for this purpose comprise a wooden core and metal flanges at the opposite ends. A plurality of steel or iron rods are driven through the length of the bobbin and overturned upon the ends of the flanges 10 to hold the flanges in place. In addition, a plurality of holes are driven through the wooden core the entire length of the bobbin and a plurality of longitudinal series of holes are bored radially into the bobbin to intersect the longitudinal holes. The bearing for 15 the bobbin passes through the center bore of the bobbin core and steam is conducted through the outwardly disposed longitudinal bores, this steam being discharged radially 20 outward through the holes in the bobbin on to the yarn. This style of bobbin is very short lived. After being in use a short time they become distorted due to the warping of the wood as a result of its severe treatment 25 by the steam. Even when this distortion is relatively slight and when the bobbin is relatively new the distortion may be noted by the irregularity in the winding of the thread, and the only remedy possible is to discard 30 the distorted bobbin and substitute a new bobbin therefor. This causes considerable expense and loss of time, and furthermore is likely to cause an improper winding of the thread upon the bobbin even when the bobbin 35 is relatively new.

The general object of this invention is to do away with these objectionable features and to provide a steam bobbin which will not become distorted due to warping, but which 40 will maintain its shape and which will therefore, last indefinitely.

A further object is to provide a bobbin having a wooden core, metal flanges at the ends of the core, and metal sleeves extending 45 entirely through the bobbin and through the flanges from which sleeves the steam passes so that the steam will not affect or distort the core.

My invention is illustrated in the accompanying drawings, wherein:—

Figure 1 is a side elevation of my device constructed in accordance with my invention.

Figure 2 is a longitudinal section of the same.

Figure 3 is an end elevation of the device.

Figure 4 is a transverse section on the line 4—4 of Figure 2.

Referring to these drawings, it will be seen that the core of my improved bobbin designated 10 is made of wood as usual. On 60 each end of this core is disposed a circular disk or flange 11 as it is called, which is of any suitable material as for instance, steel or bronze. Between the ends of the core 10 and the metallic flanges or disks, there is 65 provided a thin gasket of rubber 12 or other suitable packing material. The center of the core is bored as at 13 to admit the spindle or other axis upon which the bobbin rotates. The core is longitudinally bored at three or 70 more points as at 14 for the admission of the steam, and bronze tubes or sleeves 15 are driven through these bores, these tubes being of sufficient length so that they may be riveted or overturned into the countersunk holes 75 in the flanges. Coacting with each of the bores 14 are a plurality of radially directed passages 16, these passages being drilled through the bronze tubes so as to provide an outlet for steam upon the face of the core. 80 These bobbins are of the same size and character as the ordinary steam bobbins and are interchangeable therewith. This bobbin has a relatively long life and in this construction, the three bronze tubes not only act to line 85 the passages 15, but also act to take the place of the wire rods ordinarily used, the tubes being overturned into the countersunk margins, and holes of the flanges being as strong as the rods. Utilizing the three tubes as 90 steam ducts and eliminating the use of unlined bores, will prolong the life of the bobbin and prevent distortion. In use, these bobbins run on spindles in a spinning frame. The flanges rest on friction pulleys which 95 rotate the bobbins to wind the thread. While I have illustrated the core as being made of wood, I do not wish to be limited to this as other fibrous materials might be used. Neither do I wish to be limited to the use of 100 this bobbin as a steam bobbin as it is applicable for use in many different circumstances.

In use, the bobbin after being wound is placed with a number of others in a container and the container is placed in a steam vat. The passages and apertures in the bobbin permit the steam to circulate through the bobbin and thoroughly steam the thread. It can also be used for dyeing thread. The 110

gaskets between the ends of the wooden core and the flanges 11 are used to prevent the thread from catching in any small aperture or cracks that might be left after fitting the flanges, and these gaskets assure that no aperture exists after the bobbin is finished. It is not necessary to bush the radial passages 16 because these are short and cut across the grain of the wood. The wood will, of course, absorb some moisture during the steaming process but it cannot absorb it from these short radial passages to any such extent that it can over the longitudinal passages. The absorption of the steam as a consequent distortion of the wood core in the old style bobbin not only distorts the wood, but also distorts the wire rods which are used to hold the flanges in place. In my improved bobbin, the tubular rods as they may be called which bush the longitudinal passages and which are overturned upon the ends of the flanges are much stiffer than the wire rods and will not bend or yield, nor otherwise become distorted.

25 I claim:—

1. A bobbin of the character described including a non-metallic core, metallic flanges disposed on the ends of the core, passages extending longitudinally through the core and flanges, interior perforated sleeves disposed in said passages and extending through the flanges, and radial passages opening upon the face of the core and communicating with the interior of said sleeves through said perforations.

2. A bobbin of the character described including a non-metallic core, metallic flanges on the ends of the core, passages extending longitudinally through the core and flanges,

metallic sleeves disposed in said passages 40 and turned over upon the faces of the flanges to thereby hold the flanges to the core, and radial passages extending through the core and opening upon the face of the core and into said sleeves.

3. A bobbin of the character described including a non-metallic core, metallic flanges greater in diameter than the diameter of the core, gaskets disposed between the ends of the core and the inner faces of the flanges, 50 the core being formed with longitudinally extending passages and tubular sleeves disposed in said passages and extending through the core, the gaskets, and the flanges overturned upon the ends of the flanges, the 55 core being formed with a plurality of radial passages extending through the face of the core and into each of said tubular sleeves.

4. A bobbin of the character described including a non-metallic core having a central 60 longitudinally extending spindle passage, flanges on the ends of the core larger in diameter than the core and having a central spindle aperture, the core being formed with longitudinally extending passages and the 65 flanges having a lining, countersunk openings and tubular sleeves extending through the passages and through the openings of the flanges and overturned under said 70 countersunk openings, the core being formed with a plurality of radial passages for each of the longitudinal passages and extending from the face of the core into said metallic sleeves.

In testimony whereof I hereunto affix my 75 signature.

JOSEPH F. BRAY.
